UNITED STATES PATENT OFFICE.

MARSHALL C. WOOD, OF CORTLAND, AND GRANT BACON FRENCH, OF TRUXTON, NEW YORK.

DESIGN FOR A TABLE TOP.

Application filed October 17, 1927. Serial No. 23,776. Term of patent 3½ years.

To all whom it may concern:

Be it known that MARSHALL C. WOOD and GRANT BACON FRENCH, citizens of the United States, residing at Cortland and Truxton, respectively, in the county of Cortland, New York, have invented a new, original, and ornamental Design for a Table Top, of which the following is a specification, reference being had to the accompanying drawing, forming part thereof, which is lined for yellow, altho other colors may be used so long as two different colors form the outline of the design illustrated.

We claim:

The ornamental design for a table top substantially as shown and described.
